John F. McCabe

UNITED STATES PATENT OFFICE.

EDWARD L. LOPE, OF BROOKLYN, NEW YORK.

DESIGN FOR A RADIANT GAS-HEATER.

58,151.

Specification for Design. Patented June 14, 1921.

Application filed November 11, 1920. Serial No. 423,490. Term of patent 3½ years.

To all whom it may concern:

Be it known that I, EDWARD L. LOPE, a citizen of the United States, residing at Brooklyn, New York, in the county of Kings and State of New York, have invented a new, original, and ornamental Design for a Radiant Gas-Heater, of which the following is a specification, reference being had to the accompanying drawing, forming part thereof.

The figure is a perspective view of a radiant gas heater, showing my new design.

I claim:

The ornamental design for a radiant gas heater, as shown.

EDWARD L. LOPE.

Witnesses:

EDITH M. CAMACK,
J. F. McCABE.
